UNITED STATES PATENT OFFICE

GEORG MARTIN KLUTE, OF OSTRE AKER, NORWAY, ASSIGNOR TO AKTIEBOLAGET SIEF-
VERT & FORNANDER, OF KALMAR, SWEDEN

MEANS FOR APPLYING LABELS OR THE LIKE UPON TWO OR MORE SIDES OF BOXES,
PARTICULARLY MATCH BOXES

Application filed February 8, 1930, Serial No. 426,870, and in Sweden February 5, 1929.

The machines hitherto used for applying labels to boxes, particularly match boxes, are usually constructed so as to feed the boxes in a string one behind the other through the machine to have the boxes first coated with a paste and then provided with labels which are thereafter caused to stick fast by pressing and further smoothed by a separate pressing mechanism, the boxes being then collected in rows into a frame for further conveyance. In order to attach labels to more than one side of the boxes it has been necessary according to the methods hitherto used to repeat the same procedure in another machine with the result that, for double labelling, twice as much work and twice as much space as in single labelling were required.

The present invention has for its object to enable the attaching of labels, banderoles, rubbing strips, or the like to two or more sides of boxes in a simple way by combining a number of single labelling machines corresponding to the number of sides to be labelled to operate in series and providing a turning mechanism between each two adjacent machines to receive the boxes discharged from one machine and deliver them to the next machine after having brought them to a suitable position for labelling therein.

In the accompanying drawings some embodiments of the invention are illustrated in a diagrammatic manner.

Fig. 1 is a side elevation and,

Fig. 2 is a plan view of an embodiment in which the boxes are fed in a straight line through two single machines arranged in series and preferably combined to form a unitary structure.

Fig. 3 is a section on the line A—B and,

Fig. 4 is a section on the line C—D in Fig. 1.

Fig. 5 is a perspective view of a detail.

Fig. 6 is a plan view of a modified form of turning mechanism and,

Fig. 7 is a section of this mechanism on the line E—F in Fig. 6.

Fig. 8 is a plan view of a modified embod-

iment of a structure comprising two single machines.

Fig. 9 is a special cross section of the turning mechanism of the structure shown in Fig. 8.

In the embodiment shown in Figs. 1 and 2 the boxes are supplied, as from a box machine or a machine for introducing drawers into shells, to the labelling machine, where they are engaged by a reciprocating piston 2 operating to move the boxes in well known way to a paste container 3, a label container 4 and a pressing device 5 to have labels attached to the upper side of the boxes. The boxes are then fed into the turning mechanism under the pressure of the succeeding boxes, said mechanism being formed with a through-extending aperture 6 (Figs. 3 to 5) to receive the boxes. The turning mechanism shown comprises a rotatable disk 7 mounted in a stationary ring 8 and provided with a toothed wheel 9 and a Geneva-stop disk 10. The toothed wheel 9 is driven by a toothed wheel 11 of the same diameter and pitch as the wheel 9, said wheel 11, however, having no teeth on half of its periphery. During a complete revolution of the respective driving shaft 12 the turning mechanism will, consequently, perform half a revolution only. In order to hold the turning mechanism against rotation during the period of time in which the toothed wheels 9 and 11 are out of mesh a cam disk 13 secured to the shaft 12 is provided which cooperates with the stop disk 10 in a way that will readily appear from Fig. 4. In order to reduce the stresses on the teeth during the acceleration of the turning mechanism the toothed wheel 11 may be formed with an auxiliary tooth 14 and the toothed wheel 9 with a corresponding stop disk 15. The shaft 12 may be driven from the same main shaft as the piston 2 in such a way as to perform one revolution for each complete feed motion of the piston 2. It is evident that the toothed wheels should be so adjusted relatively to each other as to be out of mesh and the turning mechanism consequently held against operation during that period of time in which the piston effects

the feeding of the row of boxes and the con-

sequent introduction of a box into the turning mechanism.

The boxes discharged from the turning mechanism are again passed to a paste container 16, a label container 17, and a pressing device 18 under the pressure of the succeeding boxes to be labelled on their surfaces now turning upwards. The boxes now labelled upon two of their sides are then collected in any appropriate way. As in this embodiment the row of boxes is fed through the two single machines by means of a single piston it may happen, due to irregularities of the boxes, that the boxes will not take up the correct position right below the label container 17. In order to adjust this position the Geneva-stop disk 10 may be provided with screw shaped shoulders 19, as shown in Fig. 5, whereby the box last discharged from the turning mechanism will always be brought to the exact position, relatively to which the positions of the paste container 16 and the label container 17 may be adjusted.

In Figs. 6 and 7 a modified embodiment of the turning mechanism is illustrated. Said turning mechanism comprises a disk 21 mounted at 20 which is formed with a number of apertures 22 situated at equal distance apart from the axis of the disk. The disk 21 may be driven by a device similar to that shown in Figs. 1 to 4 or simply by a pawl and ratchet gear rotating the disk through an angle corresponding to the angular distance between two adjacent apertures for each box supplied. The boxes will thus be moved half a revolution and then ejected by means of a piston 23 to be labelled in the second single machine. As an advantage of this construction it may be mentioned that, provided a sufficient number of apertures is formed in the disk, the label first applied will have time to get dry sufficiently so as not to be displaced in the feeding of the box then to follow.

A third embodiment of the invention is illustrated in Fig. 8 in which the boxes supplied to the labelling machine A are first passed below a paste container 3¹. Then they are engaged by a reciprocating piston 24 operating to move the boxes to a label container 4¹ and a pressing device 5¹. By thus passing the boxes directly to the label container the piston 24 will secure a high accuracy as regards the exact position of the boxes during the labelling operation. Detachably mounted to the labelling machine A is a turning apparatus B the turning mechanism of which comprises a rotatable cylinder 27 mounted in a stationary ring 9¹, and adapted to receive the boxes discharged from the machine. To this end the middle portion of said cylinder bounded by two planes parallel to the axis of the cylinder has been removed, and into the space 28 thus obtained, see Fig. 9, the box is fed under the pressure of the suc-

ceeding boxes. The driving device for the cylinder may be similar to that shown in Figures 1-4 thus effecting a rotation of the cylinder through half a revolution between those periods of time in which the piston 24 effects the feeding of the row of boxes and the introduction of a box into the turning mechanism. The box thus turned with its labelled side down is fed out of the cylinder by means of a reciprocating piston 25 entering the space 28, 75 and under the pressure of the succeeding boxes it is delivered to the second labelling machine C detachably mounted to the turning apparatus B and operating in the same manner as labelling machine A. Thus, after 80 passing below a paste container 16¹ the boxes are engaged by a reciprocating piston 26 operating to move the boxes to a label container 17¹ and a pressing device 18¹, whereupon the boxes now labelled upon two of their sides 85 are collected in any appropriate way.

For applying labels, banderoles, or rubbing strips to two adjacent sides of a box the turning mechanism shown in Figs. 6 and 7 may be used, in which case the number of apertures of the turning mechanism should be a multiple of 4. The boxes may in such case be ejected by means of a piston after a rotation of 90° or 270°, the said last mentioned angle being the most favorable one as far as the 95 drying of the label is concerned.

What I claim is:—

1. A device for attaching labels to two sides at least of boxes, particularly match boxes, comprising a number of machines for single 100 labelling corresponding to the number of sides to be labelled, which are combined to operate in series, and means to receive the boxes discharged from one machine, turn them to the position required for labelling in the next machine, and deliver them to said next machine, each of said machines for single labeling being complete and detachable in order to be temporarily used when one label only is to be attached to each box. 105

2. A device for attaching labels to two sides at least of boxes, particularly match boxes, comprising in combination a number of machines for single labelling corresponding to the number of sides to be labelled, 115 which are arranged to operate in series, and rotatable means provided between each two successive machines to receive the boxes discharged from one machine, turn them to the position required for labelling in the next machine, and deliver them to said next machine, each of said machines for single labeling being complete and detachable in order to be temporarily used when one label only is to be attached to each box. 120

3. A device for attaching labels to two sides at least of boxes, particularly match boxes, comprising in combination a number of machines for single labelling corresponding to the number of sides to be labelled, which are 130

arranged to operate in series, and a rotatable disk provided between each two successive machines and apertured to receive the boxes discharged from one machine, turn them to the position required for labelling in the next machine, and deliver them to said next machine, each of said machines for single labelling being complete and detachable in order to be temporarily used when one label only is to be attached to each box.

10 4. A device for attaching labels to two sides at least of boxes, particularly match boxes, comprising in combination a number of machines for single labelling corresponding to the number of sides to be labelled, which are arranged to operate in series, and a rotatable disk provided between each two successive machines and formed with apertures adapted each to receive a box discharged from one machine and deliver it to the next machine after a certain rotation of the disk.

15 5. A device for attaching labels to two sides at least of boxes, particularly match boxes, comprising in combination a number of single labelling machines arranged to operate in series, a turning mechanism between each two successive machines to receive the boxes discharged from one machine, turn them to the position required for labelling in the next machine, and deliver them after turning to said next machine, and means on said turning mechanism to bring every box when discharged from the turning mechanism to a predetermined position.

20 35 In testimony whereof I have signed my name.

GEORG MARTIN KLUTE.
